MECHANICAL CLOTHES DRYING APPLIANCE
FOR DOMESTIC USE

Harry P. Houser, Vinton, Iowa

Application September 4, 1947, Serial No. 772,168

3 Claims. (Cl. 34—164)

1

This invention relates to a mechanical clothes drying appliance for domestic use.

It is an object of the present invention to provide a clothes drying appliance which will be adapted to receive clothes and cause them to be agitated while heated air is extended over the same and wherein there is provided ozone and ultraviolet light for freshening the clothes while they are being agitated and dried.

It is another object of the present invention to provide a mechanical clothes drier which is particularly adapted for home use, which is of simple construction, inexpensive to manufacture, compact and consumes little space in the laundry, which can be set up for operation by a simple attachment of an electric plug to a wall receptacle, and efficient in operation.

For other objects and for a better understanding of the invention, reference may be had to the following detailed description taken in connection with the accompanying drawing, in which

Fig. 1 is a side elevational view of the clothes drying appliance embodying the features of the present invention with portions broken away to show the interior of the same.

Fig. 2 is a cross-sectional view, in elevation, taken generally on line 2—2 of Fig. 1.

Fig. 3 is a transverse cross-sectional view taken on line 3—3 of Fig. 1.

Fig. 4 is an enlarged detail view taken on line 4—4 of Fig. 1 and showing the operating mechanism for the clothes fluffing elements.

Fig. 5 is an enlarged cross-sectional view of the operating mechanism for the fluffing elements taken generally on line 5—5 of Fig. 4.

Referring now to the figures, 10 represents a casing which is open at the top as indicated at 11 and which has a cover 12 that is hinged at 13 to the top of the casing and through the opening 11 there can be extended clothes which are to be dried. These clothes are placed into a compartment 14 and upon fluffing elements 15 and 16 which are respectively hinged as indicated at 17 and 18 to inwardly extending portions 19 of the casing to be raised for the purpose of loosening and fluffing the clothes while heated air is being passed through them. The fluffing action is accomplished by opposed elements 15 and 16 having fingerlike members 21 and 22, respectively, with the fingerlike members of these elements alternating and fitting in the spaces between the fingers. These fluffing elements are preferably formed of metal to be rigid and capable of supporting the clothes and to lift or elevate them.

On the portion 18 is a bracket 24 in which is 65 a

2

journalled a shaft 25 with a pulley wheel 26 thereon. This shaft has a cam 27 adapted to cause the reciprocating and alternate movement of links 28 connected respectively with arms 29 of the respective elements 15 and 16. These links 28 are curved as indicated at 31 to be fitted upon and retained by the cam 27. As the cam 27 is rotated, the elements 15 and 16 will be alternately lifted to raise and fluff the clothes within the chamber 14.

On a bracket 32 connected to the side of the casing, there is mounted an electric motor 33 which is connected by a belt 34 with the pulley 26. This motor is supplied with electric current by a cable 35.

This same cable 35 supplies current to an electric heating element 37 depending from a plate 38 mounted centrally within the casing and upon brackets 39. This same plate 38 supports an ozone producer 41. At the top of the casing there is provided an exhaust fan device 42 which, when operated, will cause air to be drawn upwardly from the bottom of the casing over the heater element 37 and ozone producer, upwardly through the elements 15 and 16 and the clothes and outwardly from the top of the casing. With the heated air, the clothes will be dried and by the use of ozone they will be freshened.

On the cover 12 is an ultraviolet ray lamp 43 which is supplied with current by a cable 44 leading from a box 45. A cable 46 may connect the appliance with a wall receptacle.

It will now be apparent that there has been provided a mechanical clothes drying appliance for domestic use which, by the use of ozone and ultraviolet rays, and preheated air, produce clothes which will have the same freshness as when dried in the sunshine or clean out-of-doors.

While various changes may be made in the detail construction, it shall be understood that such changes shall be within the spirit and scope of the present invention as defined by the appended claims.

I claim:

1. A mechanical clothes dryer comprising a substantially enclosed housing having a hinged cover, an exhauster positioned on the upper end of the housing and communicating with the interior thereof, opposed clothes carrying and fluffing elements positioned in the housing and having spaced fingerlike members extended therefrom and positioned in the lower part of the housing with the fingerlike members of each element alternating and fitting in the spaces between the fingers of the other element, and means

alternately raising and lowering the said fingerlike elements.

2. In a mechanical clothes dryer the combination which comprises a substantially enclosed housing having a hinged cover, and an exhauster positioned on the upper end of the housing for drawing air through the housing, a horizontally disposed partition spaced from the upper end of the housing providing a clothes compartment, said partition including opposed clothes carrying and fluffing elements and having spaced fingerlike members with the fingerlike members of one element alternating and fitting in the spaces between the fingerlike members of the other element, means alternately raising and lowering the said fingerlike elements and a heating element in the housing positioned below the said partition.

3. In a mechanical clothes dryer the combination which comprises a substantially enclosed housing having a hinged cover, and an exhauster positioned on the upper end of the housing for drawing air through the housing, a horizontally disposed partition spaced from the upper end of the housing providing a clothes compartment, said partition including opposed, clothes carrying and fluffing elements and having spaced fingerlike members with the fingerlike members of one element alternating and fitting in the spaces between the fingerlike members of the

other element, means alternately raising and lowering the said fingerlike elements and a heating element in the housing positioned in the lower part of the housing and in the path of air passing therethrough, means pivotally mounting the said fingerlike elements in the housing, said fingerlike elements having depending arms, an eccentric having pins thereon, rods connecting the eccentric through the pins thereof to the depending arms of the fingerlike elements, and means actuating the said eccentric.
